UNITED STATES PATENT OFFICE.

JULIUS DREYFUSS, OF NEW YORK, N. Y.

DESIGN FOR A CHENILLE ORNAMENT.

SPECIFICATION forming part of Design No. 15,738, dated January 20, 1885.

Application filed August 14, 1884. Term of patent 3½ years.

To all whom it may concern:

Be it known that I, JULIUS DREYFUSS, a citizen of the United States, residing at New York, in the county and State of New York, have invented and produced a new and original Design for Chenille Ornaments, of which the following is a specification, reference being had to the accompanying drawings, forming part thereof.

10 The nature of my design is fully illustrated in the accompanying drawing, which represents in elevation a strip of chenille containing my design.

15 The object of my invention is to furnish a new and effective design for strips of chenille.

The body *a* is circular in general configuration, but varies in size, being largest at the

middle part, *b*, from which point it tapers uniformly toward each end, where it terminates in a small cord, *e*. *c* represents a flat coil or 20 spiral extending the length of the strip. The spiral, which is very prominent the greater part of the body *a*, decreases in size as the ends are approached, and is finally lost in the terminal cords *e*.
25

What I claim as new, and desire to secure by Letters Patent, is—

The design for chenille ornaments herein shown and described.

JULIUS DREYFUSS.
